JAMES W. DOOLITTLE, OF STAMFORD, CONNECTICUT.

FORCE-FEED OIL-CUP.

1,359,583.

Specification of Letters Patent. Patented Nov. 23, 1920.

Application filed November 28, 1919. Serial No. 340,967.

To all whom it may concern:

Be it known that I, JAMES W. DOOLITTLE, a citizen of the United States, residing at 93 Grove St., Stamford, county of Fairfield, State of Connecticut, have invented an Improvement in Force-Feed Oil-Cups, of which the following is a specification.

This invention has for its object to provide a force feed oil cup, the parts of which may be secured together by a single operation of a press, which shall have no removable parts, which may be produced at much less expense than any oil cup now known to the trade, and which shall be equal to or superior in its operation to the various more expensive types of oil cups now in use.

With these and other objects in view I have devised the novel structure which I will now describe referring to the accompanying drawing forming a part of this specification and using reference characters to indicate the several parts.

Figure 1 is an elevation of my novel force feed oil cup as in use;

Fig. 2 a longitudinal section thereof showing the piston down, and

Fig. 3 is a disassembled view of the parts.

10 denotes the hub of my novel oil cup, 11 the reservoir, and 12 the cap. The hub is provided with a longitudinal hole 13 and with a male thread 14 for attachment to a bearing. The reservoir is drawn to cup shape from sheet metal and is provided with a hole 15 in its bottom to receive the upper end of the hub, the metal surrounding the hole resting against a shoulder on the hub and the parts being rigidly and permanently secured together by heading down the upper end of the hub, as at 16. The reservoir is provided near its upper end with an oil hole 17. The upper end of the reservoir is provided with slots extending downward for a short distance leaving tongues 18 between them.

45 The cap is drawn to cup shape from sheet metal leaving a curve, as at 25, at the intersection of the side and base, and fits the outside of the reservoir with a slide fit, so that the slight amount of oil which is unavoidable between the reservoir and the cap will make the reservoir not only dust tight but practically air tight. The piston comprises a flanged leather washer 19 which lies between metallic washers 20 and 21 and is rigidly secured to the lower end of the piston rod 22. The end of the piston rod is passed

through holes in the three washers, the upper washer resting against a shoulder on the rod, and the rod being headed as at 23 to secure the parts of the piston rigidly thereto. The upper end of the piston rod is shouldered in the same manner, is passed through a central hole in the base of the cap, the cap resting against the shoulder, and the piston rod and piston are rigidly and permanently secured to the cap by heading the outer end of the piston rod, as at 24.

Having secured the reservoir to the hub, and the piston and piston rod to the cap, the piston is placed within the reservoir and the cap slid to place outside the reservoir, as in Fig. 1, after which the assembled parts are placed in a press and the reservoir and cap forced inward relatively to each other, the effect of which is, through the engagement of the tongues at the outer end of the reservoir with curve 25 of the cap, to curve the tongues over inward, as clearly shown in Fig. 2, thereby locking the cap permanently to the reservoir but leaving the cap free to be moved longitudinally. The locking is effected through the engagement of the piston when it is drawn outward with the inwardly curved tongues on the reservoir which render it practically impossible to separate the cap from the reservoir.

The operation will be obvious from the drawing and description. To fill the reservoir, the cap is drawn outward to the limit of its movement which leaves oil hole 17 uncovered. The reservoir is partly or wholly filled through the oil hole and then the cap is pressed downward to force the oil into the bearing to which the structure is attached.

It will be seen from the foregoing that I have devised an oil cup having a cap which is free to slide up and down upon the application of pressure by hand, but is not in any manner interfered with by any spring action; in fact I eliminate the spring altogether, the cap and piston being positioned by, and receiving their set from, the hand only. This is a much more satisfactory proposition, as constructed on such a basis the feed of the oil will be in the quantities required and at the time desired, and the oil in my structure will not be constantly subjected to a pressure and be feeding forward when it is not necessary.

Having thus described my invention, I claim:

1. An oil cup comprising a reservoir, a

- free sliding hand pressed and set cap constructed so as to slide over the reservoir, a piston having a rod fixedly secured to the cap, and means formed integral with the upper edge of the reservoir for providing a lock between said reservoir and the cup after they have been assembled.
2. An oil cup comprising a reservoir having tongues at its outer end, a free sliding hand pressed cap adapted to slide over the reservoir and a piston having a rod secured to the cap, said tongues being turned inward after assembling into position to be engaged
- 10

by the piston when drawn outward, whereby detachment of the cap from the reservoir is 15 prevented.

3. An oil cup embodying a reservoir having a centrally positioned exit at the bottom and tongues at its upper end, a free sliding hand pressed cap adapted to slide over the 20 reservoir, and a piston fixedly secured to the cap by a suitable piston rod, said tongues being curved inward into position to be engaged by the piston when drawn outward.

In testimony whereof I affix my signature. 25
JAMES W. DOOLITTLE.
